UNITED STATES PATENT OFFICE.

WILLIAM A. CONANT, OF PAW PAW GROVE, ILLINOIS.

OBSTETRICAL HARNESS.

SPECIFICATION forming part of Letters Patent No. 447,870, dated March 10, 1891.

Application filed February 6, 1889. Renewed September 8, 1890. Serial No. 364,224. (No model.)

To all whom it may concern:

Be it known that I, WILLIAM A. CONANT, a citizen of the United States, residing at Paw Paw Grove, in the county of Lee and State of Illinois, have invented certain new and useful Improvements in Obstetrical Harness, of which the following is a specification, reference being had therein to the accompanying drawings.

10 My invention relates to an improvement in obstetrical supporters or harness; and it consists in the construction and arrangement of parts hereinafter described and claimed.

The object of my invention is to provide a 15 simple, efficient, and durable harness for obstetrical purposes. I attain this object by the device illustrated in the accompanying drawings, wherein like letters of reference indicate corresponding parts in the several 20 views, and in which—

Figure 1 is a perspective view of my harness, and Fig. 2 is a top view.

In the drawings, A represents a belt or waistband constructed of a broad band with 25 tapering ends. The width of the band is essential to prevent injury to the back. Secured to the tapering ends of the band A are straps or stirrups B, formed of an unyielding material. They are extended down or forward 30 for some distance, and are then turned and carried back to a point in easy reach of the patient's hands. The ends of these stirrups are looped, as at b, the loops being adapted to be increased or diminished in size 35 to adjust the harness to different-sized persons. The ends of the straps B have buckles or clasps b' thereon, which are passed over the strap to retain the loops or handles in the adjusted positions.

40 In the fold of the straps B at the forward end are placed sandals or rests C for the feet, the under sides of which are provided with lubricated or anti-friction grooves c, in which the straps are placed, thereby allowing an 45 easy movement of the straps back or forth, as the case may be.

To support the band A and to retain it in its adjusted position, suspenders D are attached to its upper edge, which are adapted 50 to be placed over the shoulder. They are preferably crossed in front. By this construction it will be readily seen that a very simple

harness is produced, and one that can be adjusted to any person.

It is a well-known fact that the half-sitting 55 position of the patient is the proper and most desirable attitude to be assumed. With this in view my invention is more particularly intended, the belt A fitting across the back above the hips and the suspenders retaining 60 it in place, so that the exertions of the patient presses the child forward.

As the most satisfactory results are attained when the pressure is brought to bear on the back of the patient, I have constructed my 65 harness so that both the pull of the arms and the push of the legs exerted on the stirrups are transmitted to the belt and back, the arrangement of the foot-rests in the fold of the straps permitting the accomplishment of this 70 result by the straps slipping easily over them.

When it is desired and necessary to bring more pressure on the abdomen, it is only necessary to cross the stirrup-straps, and thus bring the ends of the belt closer together. 75

I am aware that many minor changes in the construction and arrangement of the parts of my device can be made and substituted for those shown and described without in the least departing from the nature and principle of my invention.

Having thus described my invention, what I claim as new, and desire to secure by Letters Patent, is—

The obstetrical device herein described, 85 consisting of the broad belt, as A, having the stirrup-straps B secured to its respective ends, said straps extending around the feet of the patient back to a point within reach of the hands, the parallel portions being unconnected to permit of their free movement over the feet, and foot-rests, as C, loosely held in the folds of the straps and provided with anti-friction grooves or guides on their outer faces to retain the straps in place and permit their 90 easy movement over the same, substantially as described.

In testimony whereof I affix my signature in presence of two witnesses.

WILLIAM A. CONANT.
